UNITED STATES PATENT OFFICE

2,078,085

AIR CONDITIONING CABINET

Gottfrid C. Lawson, Canton, Ohio

Application July 31, 1933, Serial No. 682,939

2 Claims. (Cl. 183—35)

This invention relates to an improved air-conditioning cabinet particularly adapted for domestic use in conditioning air generally as well as for the dehydrating operation.

5 The primary object of the invention is to provide an air conditioning apparatus for conditioning in the home or other living quarters, which is convenient, compact, highly efficient and sanitary and may be manufactured at a relatively low 10 cost.

Another object of the invention is to provide an air-conditioning apparatus which is particularly adapted for domestic service and which may be manufactured at such cost as to bring it within 15 the realm of the average household budget.

Another object is to provide apparatus of the type specified embodying parts of a simplified character which may be conveniently assembled and disassembled for cleaning purposes and for 20 replacement and repair without the services of a skilled mechanician.

The foregoing and other objects and advantages will become apparent in view of the following description taken in conjunction with the 25 drawings, wherein:

Figure 1 is a view in elevation of a cabinet embodying the features of the present invention with the outer wall partly broken away to show the interior construction;

30 Fig. 2 is a substantially central transverse section of Fig. 1 taken on the line 2—2 of the latter figure;

Fig. 3 is a fragmentary view of a floor or air-distributing plate used with the cabinet, particularly showing the arrangement of the heating coils and air-inlet and distributing nozzles;

Fig. 4 is an enlarged vertical sectional view of the air-conditioning unit;

Fig. 4a is a fragmentary detail view of the end 40 cover plate clamp member for said unit;

Fig. 5 is a view in end elevation of the air-conditioning unit; and

Fig. 6 is a detail view in elevation of one of the baffle members or partitions comprised in the 45 unit.

Referring in detail to the drawings, particularly Figs. 1 and 2, the cabinet has an article-containing compartment A, defined by side walls 5a, 5b, 5c, and 5d, a top 5e and a floor 5f. The 50 walls of the cabinet are preferably insulated by any suitable means as at 5g to prevent loss of heat and air. The lower portion of the cabinet is provided with a housing or chamber 6 for air-conditioning and circulating apparatus, to be described. Extending horizontally across the cabi-

net are a plurality of hanger bars or rods 7, which are removably inserted in sockets 8, open at their upper extremities as at 8a to permit ready removal and replacement of said rods.

At one side of the cabinet is a return air duct 9, which at its upper end communicates with a branch duct 9a positioned at the top of the compartment A to receive the air direct therefrom and provided with a plurality of inlet openings 9b. At its lower or outlet end, the said return duct 9 fits into the inlet 10 of an air-conditioning unit generally indicated at C.

This air-conditioning unit, shown more or less in detail in Figs. 2, 4 and 5, is preferably in the form of a drum and comprises an outer side casing or wall 11, a plurality of removable baffle members or partitions 12, one of which is shown in detail in Fig. 6. These members are each provided with spacers 12a and are also formed with a cut-out portion 13, or are in effect segmental and have the said portions or slots 13 alternately positioned with respect to the casing 11, so as to direct the air in a tortuous path through the chambers 14a, 14b, etc., defined by the said partitions. Thus, the air coming in through the inlet 10 passes downwardly through the end chamber 14' into the chamber 14a and up through the latter and then down through the chamber 14b, and continues this cycle until it reaches the outlet opening 15 of the unit.

The chambers 14a, 14b, etc. are preferably packed with suitable air filtering and conditioning medium which may be of any appropriate type for the function to be performed by the cabinet. For general use, I prefer to pack said chambers with bronze wool and charcoal. This mixture serves to filter the air and absorb moisture therefrom and also lends itself to impregnation by suitable chemicals if the use of the latter is desired.

It should be understood that these chambers may be provided with any suitable means for humidifying, dehumidifying, fumigating or otherwise treating the air in conformity with the character of work performed, and that the temperature of the unit may be regulated in any suitable manner to assist in bringing about the desired result.

To facilitate removal and replacement of the baffle partitions 12, the rear wall 11a of the casing 11 is removably secured to the side walls of said casing by means of a clamp bracket construction, generally indicated at 16, note Fig. 4a. By loosening the screw 16a, the end wall 11a may be readily removed to permit access to the in-

- terior of the casing 11. At the bottom of the condenser is a drain pipe 17 provided with a trap 17a to permit the moisture of condensation to drain from the unit. The pipe 17 preferably 5 drains into a channel or longitudinal slot 17b formed in the supporting member 26, said channel in turn draining into a drain pan or like container 17c, slidably supported in guide brackets 17d at the bottom of the cabinet.
- 10 The front end of the unit C is provided with an end wall or head 11b, which is formed with an inlet port or slot 18, and coacting with the said end wall 11b is an adjustable door 19 provided with a port or slot 19a adapted to coact 15 with slot 18, the said door being secured under tension against the end wall 11b by means of a bolt 20 and spring 20a.

To provide for convenient adjustment of the door 19, the latter connects through the medium 20 of a connecting rod 21 with a link 22 secured on a rod 36, which is rotatably supported by a pedestal bracket 23 and controlled from the panel board of the cabinet, to be described. By adjusting the slot 19a with respect to the slot 18, 25 the amount of atmospheric air admitted into the conditioning unit C may be accurately controlled or regulated. Thus, if it is desired to use the cabinet as a conditioning unit for the air in the room, the slot 18 may be opened to the atmosphere and the cabinet door, not shown, partly or fully opened to permit the conditioned air to escape into the room. For drying clothing, or other articles, the slot 18 is preferably fully closed, and is only opened when it is desired to 30 introduce atmospheric or room air into the system.

The unit C is preferably supported upon an adjustable supporting bracket 24 provided with a handle 24a, said bracket being pivotally mounted 40 in bearing lugs 25 provided on the frame member 26. By this means, the unit may be readily elevated so that the inlet 10 telescopes into the end of the return conduit 9, and, conversely, may be readily lowered when it is desired to remove it 45 from the housing 6, the latter being provided with a door 25 to permit removal of said unit.

The outlet 15 of the unit C telescopes into an annular fan housing 27, note particularly Fig. 2 in which a fan 27a is mounted, the latter being 50 driven by means of a motor 28. The housing 27 is provided with a surrounding filter chamber 27b, which communicates at its upper extremity with a duct 29, the latter opening out into a chamber 30 formed at the bottom of the cabinet. 55 The annular filter chamber 27b is preferably packed with a suitable filtering and/or conditioning medium such as bronze wool or the like, and acts as a further means of conditioning and treating the air and precipitating moisture therefrom prior to its admission into the cabinet. 60 The lowermost portion of the chamber 27b is provided with a drain pipe 27c which also drains into the channel 17b.

The entire assembly, including the unit C, motor 28, fan housing 27 and chamber 27b, is mounted on a frame member or beam 26a anchored in rubber or like resilient mountings 26b.

At the bottom of the compartment A, I preferably dispose a baffle or air-distributing plate 70 31. This plate forms the upper boundary or ceiling of the chamber 30 and is preferably provided with a plurality of nozzle members 32. These members, as shown, are arranged in groups and are formed with curved segmental baffle caps 75 32a which serve to deflect air in such a manner

that it travels upwardly with a circular movement and is thus substantially evenly distributed throughout the drying chamber or compartment A.

Within the chamber 30 a plurality of heating 5 coils 33 are disposed, to heat the air flowing upwardly into the drying chamber. These coils may be of any suitable size and capacity and may be provided with suitable controls or rheostats to vary the temperature as desired. 10

At the exterior of the cabinet is a suitable control panel 34 provided with suitable indicia and a control handle 35, which is connected to the rod 36. A switch 37 for the fan motor is provided, and a further switch 38 for the heating 15 coil circuit is also provided.

To provide a reliable and accurate means for cutting off the apparatus after the clothing or other articles in the compartment A have been fully dried, I preferably utilize a type of switch 20 member which automatically cuts off through the dehydrating action of a wet article in contact therewith. This switch unit is shown in Fig. 1 and consists of switch wires 40 and 41, which are the unconnected terminal extremities of 25 the switch circuit and may be of relatively fine wire and are wound upon one of the rods 7 or other suitable core in the form of a coil 42. These wires 40 and 41 are connected in series with a relay switch or the like, not shown, which 30 in turn is connected into the main circuit. The coil extremities of the switch wires are partly or wholly uninsulated and may be spaced a very slight distance apart from each other when winding the coil 42. At one end of the coil 42, I mount a clamp 43. The relay switch is organized to close the main circuit when energized and open 35 said circuit when de-energized. A suitable step-down transformer, also not shown, is interposed in the switch circuit to reduce the voltage from 40 the main line to a point commensurate with the switch circuit.

The operation of the automatic switch is as follows: When a wet article of clothing or a cloth or the like is clamped on the coil 42, the wires 45 40 and 41 are shorted and form a conductor for the electric current thereby energizing the relay switch and maintaining the circuit closed. As the article becomes dry, the shorting action ceases and the relay switch is de-energized and the main 50 circuit is broken, stopping the machine. The initial moisture content of the cloth clamped on the coil 42 may be regulated so that it will cease 55 its short-circuiting action over varying periods of time, and thus ensure that the remaining clothing in the compartment A is fully dried before the circuit is broken.

From the foregoing, the operation of the apparatus will be readily understood. Assuming that the cabinet is to be used for drying clothing, the 60 latter would be hung upon the rods 7 in the compartment A. The motor is then started and a circulation of air is caused to travel in a cycle including the duct 29, chamber 30, compartment A, passing out from said compartment through 65 outlets 9b into the outlet duct 9a and return duct 9, and from the latter into the air-conditioning unit C through the inlet 10. The air at this point may have a certain amount of atmospheric or room air admitted thereto, if desired, by regulating the opening 18 of the unit C. The air passes 70 into the unit C and is conditioned and treated in the said unit and thence passes into the auxiliary treating chamber 27b. From this chamber, the air passes into the duct 28 and repeats the cycle. 75

When it is desired to use the cabinet or apparatus as an air-conditioning unit, the door to compartment A (not shown) may be opened and the control knob or handle 35 turned so that the slot 18 is open to the room or outside atmosphere, the coils 33 serving to control the temperature of the conditioned air and the unit C serving to filter and humidify or dehumidify the air as required. In this connection, it will be understood 10 that moisture or water at a suitable temperature may be supplied to the unit C by any desired means, not shown, but obvious to the average layman.

The unit may also be used for fumigating and 15 otherwise treating articles of clothing, as will be readily understood. The entire cabinet may be made in sizes suitable for domestic as well as commercial use and is compact and requires very little space as compared with the larger installations. The apparatus has been found highly efficient and may be readily and accurately controlled.

I claim:

1. In a conditioning unit of the class described, 25 including an air cleaning chamber, a fan and an

air heating chamber, said cleaning chamber comprising a drum having a plurality of baffles therein in separating the drum into a circuitous chamber, means in said chamber to accumulate foreign material being carried through the chamber by the air, said fan being connected to one end of 5 said chamber and adapted to circulate air through the chamber and deliver said air to said heating chamber.

2. In a conditioning unit of the class described, 10 including an air cleaning chamber, a fan and an air heating chamber, said cleaning chamber comprising a drum having a plurality of baffles therein in separating the drum into a circuitous chamber, means in said chamber to accumulate foreign 15 material being carried through the chamber by the air, said fan being connected to one end of said chamber and adapted to circulate air through the chamber and deliver said air to said heating chamber, said drum and fan being removable from 20 the heating chamber and said drum being separable from said fan and having a removable wall through which the air cleaning material can be removed.

GOTTFRID C. LAWSON. 25
